UNITED STATES PATENT OFFICE.

HERBERT H. MOOR, OF DAVENPORT, IOWA.

DESIGN FOR A RADIATOR-CAP ORNAMENT.

55,072.

Specification for Design.

Patented May 4, 1920.

Application filed August 27, 1919. Serial No. 320,312. Term of patent 3½ years.

To all whom it may concern:

Be it known that I, HERBERT H. MOOR, a citizen of the United States, residing at Davenport, in the county of Scott and State of Iowa, have invented a new, original, and ornamental Design for a Radiator-Cap Ornament, of which the following is a specification, reference being had to the accompanying drawing, forming part thereof.

The figure of the drawing is a perspective of a radiator cap ornament, showing my new design.

I claim:

The ornamental design for a radiator cap ornament, as shown.

In testimony whereof I affix my signature.

HERBERT H. MOOR.
